Primary Examiner — Deanna L Pratt

(74) Attorney, Agent, or Firm — Michael Best & Friedrich LLP

(57) **CLAIM**

We claim the ornamental design for a knob for a cutter, as shown and described.

DESCRIPTION

FIG. 1 is a rear view of a knob of a cutter.

FIG. 2 is a rear perspective view of the knob of FIG. 1; and, FIG. 3 is a front perspective view of the knob of FIG. 1. The cutter and portions of the knob shown in broken lines are included for the purpose of illustrating environment and form no part of the claimed design.
